UNITED STATES PATENT OFFICE.

WILLIAM CLEMSON, OF MIDDLETOWN, NEW YORK.

BUCK-SAW FRAME.

SPECIFICATION forming part of Letters Patent No. 281,887, dated July 24, 1883.

Application filed May 1, 1883. (Model.)

To all whom it may concern:

Be it known that I, WILLIAM CLEMSON, of Middletown, Orange county, New York, have invented a new and useful Improvement in 5 Buck-Saw Frames, of which the following is a full, clear, and exact description.

This invention consists in the employment of two braces reaching from the center of the cross-piece of the frame of the saw diagonally up to the upper ends of the side pieces of the frame, whereby the frame is braced in a cheap and very efficient manner, as hereinafter fully described, and pointed out in the claim.

Reference is to be had to the accompanying 15 drawing, in which the figure is a side elevation of my new and improved buck-saw frame.

The side pieces, *a a*, of the frame, the cross-piece *b*, and the tie-rod *c* are all of ordinary construction, and the saw-blade *e* is secured at 20 its ends in the side pieces, *a a*, in the ordinary manner.

d d represent the braces of the frame, which reach from about the center of the length of the cross-piece *b* diagonally up to the upper 25 ends of the side pieces, *a a*. At the lower ends the braces *d d* are held in place upon the cross-piece *b* by means of the staple *f*, or other suitable fastener. At their upper ends they are held in place by the tie-rod *c*, passing 30 through suitable holes made in their upper ends, as will be understood from the drawing, and at their upper and lower ends they are beveled to fit upon the cross-piece and against

the side pieces, and at their lower ends the braces abut against each other, to prevent any 35 sliding movement upon the cross-piece *b* when the nut *g* is turned for straining up the frame.

The action of the frame is as follows: Upon the screw *g* being turned the upper ends of the side pieces will approach each other against 40 the action of the braces *d d*, which will depress the cross-piece *b* in the center, which depression of the cross-piece permits the upper ends of the side pieces being drawn closer together than they would be if the said cross-piece remained straight, and consequently the straining of the saw-blade to greater extent, and the frame, as a whole, at the same time braced and made more rigid and firm than by any system of bracing known to me. Besides, 45 50 the frame, as a whole, is cheap, durable, and not liable to get out of order.

Having thus described my invention, I claim as new and desire to secure by Letters Patent—

In a buck-saw frame, the combination, with 55 the side pieces, *a*, and central straight cross-piece, *b*, of the straight diagonal braces *d*, having beveled ends, and secured to the center of the cross-piece, with their ends abutting, by the staple *f* and the rod *c* passing through the 60 ends of the braces *d*, substantially as shown and described.

WILLIAM CLEMSON.
